(Cl. D34—4)

To all whom it may concern:

Be it known that I, Mieczyslaw Szrajer, a citizen of Poland, residing at Forest Hills, New York, in the county of Queens and State of New York, have invented a new, original, and ornamental Design for a Doll or Similar Article, of which the following is a specification, reference being had to the accompanying drawing, forming part thereof.

In the drawing

Fig. 1 is a front elevational view of a doll or similar article, showing my new design;

Fig. 2 is a side elevational view thereof.

I claim:

The ornamental design for a doll or similar article, substantially as shown.

MIECZYSLAW SZRAJER.
